REFRIGERATED DISPLAY CASE FOR DISPENSING FROZEN FOODS

Benjamin Lewis, 1527 Taylor Ave., Bronx, N.Y.

Filed Nov. 22, 1960, Ser. No. 62,922

Term of patent 14 years

(Cl. D80—11)

The FIGURE is a front perspective view taken from the top and left end of a refrigerated display case for dispensing frozen foods embodying my new design, the rear being substantially plain, and the right end being the same as the left end shown. The dominant features of my design reside in the full line portions of the drawing.

I claim:

The ornamental design for a refrigerated display case for dispensing frozen foods, substantially as shown and described.
